UNITED STATES PATENT OFFICE.

THOMAS HARDING, OF NEWARK, NEW JERSEY, ASSIGNOR TO J. L. SOMMER MANUFACTURING CO., A CORPORATION OF NEW JERSEY.

DESIGN FOR A COMBINED BOTTLE OPENER AND PICK.

43,278.

Specification for Design.

Patented Nov. 26, 1912.

Application filed September 7, 1912. Serial No. 719,249. Term of patent 14 years.

To all whom it may concern:

Be it known that I, THOMAS HARDING, a citizen of the United States, residing at Newark, in the county of Essex and State of New Jersey, have invented a new, original, and ornamental Design for a Combined Bottle Opener and Pick, of which the following is a specification, reference being had to the accompanying drawing, forming part thereof.

Figure 1 is a side view of a combined

bottle opener and pick, showing my new design, and Fig. 2 is an edge view of the same.

I claim:

The ornamental design for a combined bottle opener and pick, as shown.

THOMAS HARDING.

Witnesses:

LEILA C. GOULD,
CHARLES MUNTRICK.
